UNITED STATES PATENT OFFICE.

JOSEPH A. METZGER, OF BUFFALO, NEW YORK.

ADJUSTABLE SHADE OR CURTAIN BRACKET.

1,311,453.

Specification of Letters Patent. Patented July 29, 1919.

Application filed January 18, 1917. Serial No. 143,265.

To all whom it may concern: Fig. 7 is a broken perspective view of the
Be it known that I, JOSEPH A. METZGER, an adjustable member of the bracket.
citizen of the United States, residing at Fig. 8 is a vertical longitudinal section
Buffalo, in the county of Erie and State of through the fixed member of the bracket
5 New York, have invented certain new and and the intermediate portion of the adjust- 60
useful Improvements in Adjustable Shade member thereof, the same being taken
or Curtain Brackets, of which the following on line $c-c$, Fig. 4.
is a specification.

Fig. 9 is a plan view of the blank from

Fig. 6 is a longitudinal section taken on transverse portion from which the longitu- 110
line $b-b$, Fig. 4. dinal member projects.

Extending from each side of the longitudinal member a short distance from said last-mentioned edge of the transverse member are two tongues 22, 23, one of which is a 5 trifle longer than the other, and at the free end of said longitudinal member the blank is cut away, as at 24, to reduce the width of said member.

The transverse member 16 is bent on the 10 fold lines 25 to provide offset end securing lugs 26. By thus offsetting said lugs the medial portion of said transverse member is brought to a position that when the fixed member is attached to the window casing 15 said medial portion is spaced from the window casing, as clearly shown in Figs. 4 and 6.

The metal of the blank between the slits 19 and 20 and the U-shaped incision 21 is 15 bent rearwardly, as at 27, as shown in Fig. 10, so that these portions assume a position out of line with the remainder of the medial portion of said transverse member, and when thus bent the metal surrounded at 25 three sides by the U-shaped incision of the blank serves as a tongue 28. The longitudinal member 15 is then bent on the fold line indicated at 29, Fig. 9, and thus assumes the position shown in Fig. 10. After this step 30 in the formation of the securing member, the short tongue 22 is bent on the fold line 30 so as to lie crosswise on the longitudinal member 15. On the tongue thus bent the tongue 23 is then folded on the fold line 31, 35 Fig. 9, and lies against the folded tongue 22, thus reinforcing the longitudinal member by providing three thicknesses of metal at this point, as shown at 32, Figs. 4 and 8. The longitudinal member 15 is then bent on the 40 fold line 33 to bring a portion of the same into a vertical position in front of the transverse member 16, as at 34, Figs. 2, 4 and 6, which may now be termed the horizontal part of the fixed member. This longitudinal member is further bent on the fold line 45 35 so that the end portion of the same is directed rearwardly over said horizontal part, as at 36, with the reduced extremity fitting into the notch 18 at the upper edge 50 of said horizontal part. This reduced portion is then bent downwardly on the fold line 37 in contact with the rear face of the medial portion of said horizontal part, as shown at 38, Figs. 4 and 11. The fixed or 55 permanent member being thus completed comprises the horizontal member 39 having an offset medial portion; a reinforced depending portion 40 whose rear face is in line with the rear faces of the securing lugs 26 60 and is adapted to lie in contact with the window casing A, as are said securing lugs, thus providing a substantial bearing for the fixed member.

By notching the reduced portion of the 65 longitudinal member of the blank 15 into

the notch of said horizontal part of the fixed member, the transverse portion 34 of the fixed member, which the longitudinal member of the blank 15 now forms, is retained against lateral movement and is also held 70 against outward or inward movement with respect to the horizontal portion by the shoulders 42 bearing against the front of said horizontal portion and by the downwardly bent portion 38 which is in contact 75 with the rear face of the offset medial portion of said horizontal member.

Through the three thicknesses of metal or the reinforced depending portion of the fixed member, a screw hole 43 is formed into 80 which is threaded a clamping screw 44.

The adjustable member is formed from a strip of metal bent longitudinally to provide a longitudinal flange 46 along one of its edges and it is also bent at one of its ends to 85 provide a trunnion-receiving or supporting arm 47, said arm being stamped to desired outline and provided in the usual way with a trunnion-receiving opening 48, the metal around said opening being bent inwardly, as 90 at 49, as is common in brackets of this type. This adjustable portion is adapted to fit between the front face of the horizontal portion of the fixed member and the rear or inner face of the transverse portion 34, the 95 upper face 50 of the flange 46 being adapted to bear against the lower edge of the lug 28 and the spaced end parts of said medial portion, the binding screw 44 being forced upwardly into contact with the lower face of 100 said flange and securing the adjustable member in any desired position on the fixed or permanent member.

Having thus described my invention, what I claim is,

1. A shade bracket comprising a fixed member formed of a single piece of sheet metal and having a horizontal part with offset securing lugs at opposite ends and a notch formed at its upper edge midway between its ends, said horizontal part being provided with transverse slits extending upwardly from its lower edge and with a U-shaped incision between said slits, and a transverse part of which the metal between 110 said U-shaped incision and said slits forms part, said transverse part being bent rearwardly from the upper edge of said slits and U-shaped incision and being directed downwardly a distance below the lower edge of 115 said horizontal part, thence forwardly and upwardly in spaced relation to the lower edge and the front face of said horizontal part, thence rearwardly into the notch at the upper edge of said horizontal part and 120 finally downwardly in contact with the rear face of said horizontal part, an elongated adjustable member fitting between said transverse part and said horizontal part and having a rearwardly extending flange in 130

contact with the lower edge of said horizontal part, and a screw passing through the depending portion of said transverse member and bearing against the underside 5 of said flange.

2. A shade bracket formed of sheet metal and comprising a fixed member and an elongated adjustable member slidable within said fixed member, said fixed member having a horizontal part offset near each end to provide securing lugs and an outwardly extending medial portion, said medial portion having a notch at its upper edge and being provided with slits extending upwardly from its lower edge and having also a U-shaped incision between said slits, a transverse part integral with said horizontal portion and merging upwardly into the latter between said slits and said U-shaped incision, said transverse part being bent rearwardly between said slits and said U-shaped incision and directed downwardly and thence forwardly and rearwardly in spaced relation to the lower edge and the front face of said horizontal part, said transverse part having tongues bent upon itself from opposite edges to provide three thicknesses of metal at the forwardly bent portion thereof and having also a reduced extremity providing shoulders and being bent rearwardly with said shoulders in contact with the front face of said horizontal part, said reduced extremity fitting into the notch at the upper edge of said horizontal part and being thence bent downwardly in contact with the rear face of horizontal part, an elongated adjustable member fitting slidably between the front face of said horizontal part and the inner or rear face 40 of said transverse part and having a longitudinal flange in contact with the lower edge

of said horizontal part and a supporting arm at one end thereof, and a binding screw passing through the reinforced forwardly projecting portion of said transverse part 45 and bearing with its inner end against the underside of said longitudinal flange.

3. A shade bracket formed of sheet metal, comprising a fixed member and an elongated adjustable member, said fixed member having a horizontal part offset near each end to provide securing lugs, an outwardly extending medial portion provided with slits extending upwardly from its lower edge, and a transverse part integral with said horizontal part and merging upwardly into the latter between said slits, said transverse part being directed rearwardly and downwardly between said slits, thence forwardly and upwardly in spaced relation to said 60 horizontal part and thence rearwardly and downwardly in rear of the outwardly extending medial portion of said fixed member, said adjustable member being adjustable between said horizontal and transverse 65 parts.

4. A shade bracket comprising a fixed member formed of sheet metal having a horizontal part provided with a notch at its upper edge and a transverse part integral 70 with said horizontal part and spaced from the front surface of said horizontal part, said transverse part being bent upwardly from the lower region of said horizontal part and having a reduced portion at its 75 upper end passed through said notch and bent downwardly in rear of said horizontal part, and an adjustable member between said transverse part and the front surface of said horizontal part.

In testimony whereof I affix my signature.
JOSEPH A. METZGER.
